[57] CLAIM

The ornamental design for a hair iron, as shown and described.

DESCRIPTION

FIG. 1 is a perspective view showing my new design held in an open position;

FIG. 2 is a top view of the present invention shown in the closed position;

FIG. 3 is a front view thereof;

FIG. 4 is a bottom view thereof;

FIG. 5 is a back view thereof;

FIG. 6 is a left side view thereof;

FIG. 7 is a right side view thereof;

FIG. 8 is a front view of the present invention shown in an open position; and,

FIG. 9 is a sectional taken along line 9—9 of FIG. 8.

The broken lines showing the cord, transformer plug, hand and other, smaller features are for illustrative purposes only and form no part of the claimed design.

The surface(s) or portion(s) of the article not shown in the drawing or described in the specification form(s) no part of the claimed design.
